COKE-OVEN DOOR OPERATING MECHANISM

Gustaf Edwin Salkvist, Pittsburgh, Pa., assignor
to Koppers Company, a corporation of Delaware

Application March 6, 1937, Serial No. 129,336

20 Claims. (Cl. 202—248)

The present invention relates to coking retort ovens in general and more specifically pertains to an improved and special means adapted to latch the removable doors of coking chambers in closed and sealed position, while the carbonization process is in progress in such chambers, and to a mechanism for actuating said latching means.

In a co-pending application of the applicant, Serial Number 129,337, which was filed of even date herewith, a novel and useful improvement in latching means for the doors of coking retort ovens has been disclosed, said improvement comprising a flexible and resilient latch-bar means adapted to be employed in place of the substantially inflexible one in customary use in the art; a latching means having the properties of flexibility and resilience furnishes many advantages amongst which are its ability to provide automatically for compensatory adjustments within itself whereby certain undesirable effects of fluctuations from that pressure initially established between the door frame and the oven door at the beginning of the carbonization period, such as for example may be engendered by unanticipated pressure of the coal charge against the door, or changes in the temperature of the door and the like, will tend to be counteracted, with the result that increased protection for the doors especially of the well-known types having yielding, metallic sealing edges is provided thereby. Latch-bars of said type also advantageously provide convenient and simple means whereby the pressure between an oven door and its door frame can be adjusted and maintained with improved refinement.

In the above-cited co-pending application, the improvement was preferably embodied as a leaf-spring or so-called "spring-latch" that was adapted to be inserted between the movable oven door and the adjacent stationary hooks provided for engaging the spring-latch. This improvement was shown in two useful embodiments. The one embodiment comprises a spring-latch that was adjustably and rotatably mounted on the door and was provided with means for moving the latch into and out of operating position so that each latching means could be an independently operative unit that did not require the intervention of an extraneous mechanism in its practical exploitation. In its other embodiment, the invention was shown as a simple leaf-spring positioned between the movable door and stationary latch-hooks in flexed condition and so disposed in respect of said latch-hooks and door that the

pressure resulting from the flexion of the spring was used to hold the movable door against its door frame. This latter embodiment of the improvement was neither mounted on the door nor provided with means for removing it from pressure-contact with the door and the latch-hooks, so that the operations of removing and replacing the spring-latch to permit respectively the opening and closing of the coking chamber must be performed by an extraneous device.

The instant application is supplementary to that disclosing the above-mentioned improvements, and by the hereinafter described invention there is furnished a simple and effective mechanism whereby a spring-latch, intended to be used in an embodiment thereof having no special actuating means directly associated therewith, can be placed into and removed from operating position with ease and precision. This is one of the objects of invention.

Another object of invention is the provision of a mechanism for the stated purpose which can, if preferred, be positioned on the pusher and door machines and also be disposed to co-act therewith in such operating procedure that both devices can be brought into position for satisfactory operation simultaneously, thereby saving the time that would otherwise be required in stationing two separate mechanisms. The invention has for further objects such other operative advantages or results as may be found to obtain in the processes and apparatus hereinafter described or claimed.

My present invention comprises essentially a mechanism adapted to provide a clamp-like action and has at least two jaws, the one of which is capable of such movement in respect of the other that the distance between them can be increased or diminished and preferably by power-driven means. According to the invention, the jaws of the clamping mechanism are adapted for movement into and out of engagement with the spring-latch assembly by the same operation of the door machine that serves to actuate the door-hook into and out of engagement with the door-hook plate. For effecting this movement the door-hook and the latch-clamp are joined by straps or connecting rods so that the motion of the one is imparted to the other. The closing and opening of the jaws of the clamping mechanism, which movements are respectively employed to flex the spring-latch or relieve it of the effects of that action, are preferably performed by a power-driven device that is individual to said jaws. By means of the present in-

vention all the spring-latches in corresponding positions at one face of a battery of ovens are operable by a single actuating mechanism, with the result that a significant part of the greater expense required to supply each spring-latch with an individual actuating means, as shown in one embodiment of my improved latching means disclosed in the hereinbefore mentioned co-pending application, is saved.

10 In the accompanying drawings forming a part of this specification and showing for purpose of exemplification a preferred apparatus and method in which the invention may be embodied and practised but without limiting the claimed invention specifically to such illustrative instance or instances:

Figure 1 is a view, in transverse vertical section, of a portion of a coke oven battery showing an oven door supported in the oven mouth by means of a flexible and resilient spring-latch and a door machine associated therewith having the customary door-hook for handling the door, and in combination with said door machine the clamping mechanism, constructed according to the present invention, for actuating the spring-latches of the door-latching means; in this figure the latch-actuating mechanism is shown in engagement with the spring-latches at such time as the door-hook is about to enter into engagement with the door-hook plate;

Figure 2 is an outline drawing of a view similar to that shown in Figure 1 but in which both the latch-clamping device of the invention and the door-hook have been lowered away from operating contact with the oven door;

Figure 3 is a plan view taken along the lines III-III of Figure 1;

Figure 4 is an enlarged fragment of Figure 1, parts being in section; and

Figures 5 and 6 are vertical sections along the lines V-V and VI-VI, respectively of Figure 4 and Figure 2.

The same reference numerals refer to the same parts in the drawings.

Referring now to the drawings, especially to Figures 1, 2 and 3, each coking oven 10 of a battery thereof is provided at each end with a removable door 11 for closing the mouth thereof during the interval that the carbonization reaction is progressing through the coal charge. Door 11 comprises the door-casting 12 and the refractory plug 13 which is adapted to fit loosely between the heating walls 14 of the battery structure when the door is placed into operating position to close the oven mouth. The interstitial spaces of the door plug and the heating walls are sealed from the ingress of air and escape of products of distillation by means of the flexible sealing-frame 15, that is affixed to the door and extends around its entire periphery, and by a co-acting door-frame 16 that entirely surrounds the oven mouth in the well-known manner. The door frame is formed as a lateral projection of the ribbed face-plates 17 which in turn serve to cover the jamb bricks 18 positioned at each end of an oven heating wall and against which they are pressed by the buck-stays 19 that serve to restrict movement in the heating walls of the battery.

Screws 25 are located at intervals around the door-casting and serve as a means for applying pressure to the flexible sealing frame so that the narrow edge 26 thereof can be pressed into such contact with the door frame, at all points thereto along, as prevents leakage of gases into or out of

the coking chamber through the interstitial spaces 27.

The latching means for supporting the oven door in the mouth of the coking chamber and for holding it in sealed position against the door frame comprises primarily the latch-hooks 28 attached to the rib 29 of the face-plate, the bracket 30 affixed to the door casting 12 by bolts 32, and the spring-latch 33 which is adapted for insertion between the movable door and the stationary 10 latch-hooks, and in which position it is also disposed to exert such pressure against said latch-hooks and the bracket 30 as will hold the sealing frame of the door against the door frame at the preferred pressure. The spring-latch assembly 15 33 itself comprises a yoke 34 within which are mounted a channel-casing 35 and a plurality of graduated metal plates 37, all said members being held together by stud bolt 38 in such fashion that they may function as a flexible and resilient 20 latch-bar, substantially as shown. The spring-latch assembly, when in operating position, and in which position it is shown in the drawings, is so disposed that yoke 34 is pressed against the surface 39 of bracket 30 and the group of metal 25 plates 31, which functions as a leaf-spring, has both ends of at least one of the longest plates in pressure-contact with their respective latch-hooks. The substantially rigid channel-casing 35 has been designed, with the configuration 30 shown, in order that it may serve two purposes, the one of which is to retain metallic plates 37 in orderly arrangement at such times as the spring-latch is relieved of all pressure thereon and the other is to serve as a means for applying 35 pressure to said plates at some specifically preferred point or points. As will be noted in Figure 3, the ends 40 of the vertical section of said casing are curved inwardly in such manner that pressure applied at the middle of the channel-casing will cause the ends thereof to bear against the longest plates of the spring assembly 37, adjacent the points where they are engaged by the latch-hooks, and to flex them so that they will be removed from contact with the latch-hooks. Yoke 45 34 is disposed to slide over said channel-casing, and if therefore clamping pressure is applied simultaneously to the outside of the vertical sections of both the yoke and the casing, these members can be moved closer together and the spring-latch assembly removed from pressure-contact with both the door-bracket and the latch-hooks. The assembly can then be moved upward and out of operating position and in so doing leave the door free to be removed from the oven mouth. 55

According to the present invention, I provide a power-driven mechanism that is adapted to furnish the clamp-like movement just described. Essentially the invention comprises a wrench-like mechanism having co-acting jaws mounted on a 60 movable stage. One of the jaws is adapted to be moved mechanically whereas the other is fixedly mounted to said stage. Furthermore, the movable stages for supporting the mechanisms for the upper and lower latches are mounted on the 65 door or pusher machine and are connected by connecting-rods with the door-hook in such manner that, during the moving of the door-hook into position for engaging the door-hook plate preparatory to withdrawing the door from the oven, the 70 wrench-like mechanisms for actuating the spring-latches at the top and bottom of the door are brought into their proper operating position for removing the pressure of the spring-latch from the door and latch-hooks, and thereafter while 75

the door-hook is being moved into actual lifting-
engagement with the hook plate, the spring-
latches are being moved out of engagement with
the latch-hooks substantially simultaneously.
5 The invention will be more clearly understood by
again referring to the drawings.

The door-machine 45, shown in Figures 1, 2,
and which is adapted to travel in parallelism
with the ends of the ovens of a battery on tracks
10 provided for the purpose, is stationed in front of
an oven door and in position to perform the oper-
ations of un-latching the door and removing it
from the oven. In Figure 2, the door-hook and
the co-movable latch-actuating mechanism are
15 shown moved downwardly and out of operating
position. In Figure 1 the ram 46 is shown as
having been moved on wheels 47 into such posi-
tion adjacent the oven door by the driven pinion
48 and the co-acting rack 49 of the ram that the
20 bumper 50 is engaged with bumper-plate 51 which
is affixed to the door. This movement of the ram
has also moved the door-hook 52 and the latch-
actuating mechanism of the invention into oper-
ating position. Door-hook 52 is mounted on
25 shaft 53 and is adapted for movement in a ver-
tical plane by power supplied from motor 54 and
which is transmitted to the door-hook respec-
tively through the spur gear reduction 55, thread-
ed sleeve 56, and threaded stem 57 which ter-
30 minates in a rack-section that meshes with gear
sector 58 supporting the door-hook.

The actuating mechanisms for the spring-
latches, adjacent the top and bottom of the door,
35 are mounted on stages 59, each stage being sup-
ported on a bracket 60 of the door machine ram
by means of crank-shaft 61. Both the upper and
lower stages are connected with the door-hook
respectively by rods 62, 63, so that said stages
40 and door-hook can be moved in unison and from
the same source of power.

In Figures 3, 4, the spring-latch actuating
mechanism of invention is shown in detail assem-
bled on stage 59. The mechanism comprises the
driving motor 64, speed reducer 65, thrust-bracket
45 66, and both the fixed front jaws 67 along with
the movable rear jaw 68 which provide the ac-
tual clamping operation whereby the spring-
latch is flexed so that it may be removed from
or restored to operating position between the
50 oven door and the latch-hooks. Movable jaw
68 is provided with ways 69 on the supporting
stage and in which they are held by grooves 70
in the fixed jaws 67 that are bolted to said stage
by bolts 71, said movable jaw being disposed to
55 slide within said ways. The movable jaw is also
provided with a cylindrical bore 71a that ex-
tends therethrough in substantial parallelism
with the ways 69 provided by the fixed jaws. A
section 72 of this bore is provided with coarse
60 threads, preferably a double thread of the Acme
type. Shaft 73 is formed preferably as a tube
having a collar 74 between which and the thrust-
bracket 66 there is interposed washer 75 of bear-
ing-metal for taking-up the pressure of the mov-
able jaw, when the latter is in pressure-contact
65 with the channel-casing of the spring-latch; the
shaft is adapted for rotation by motor 64 oper-
ating through speed-reducer 65, and is rigidly con-
nected with the slow-speed shaft of said re-
ducer. At its end towards the door, a short sec-
tion "A" of shaft 73 is turned to give a running
fit against the top of the threads of the jaw, said
section operating as a guide toward preventing
lateral movements of said shaft so that it will
5 travel smoothly in the bore of the jaw and also

assist in its entrance thereinto. The threads 76
of hollow shaft 73 are adapted to co-act with
those of jaw 68, and when these threaded parts
are in engagement, said jaw can be either moved
towards or retracted from fixed jaws 67 by ap-
5 propriate rotation of said shaft. Threads 76
are so disposed in respect of the shaft 73, the
movable jaw and channel-casing 35 that when
the jaws have been brought together sufficiently
10 to remove yoke 34 and spring-leaves 37 from con-
tact respectively with bracket 30 and latch-
hooks 28, said threaded section 76 will have en-
tirely emerged from the threaded part of the
jaw so that any further rotation of the hollow
15 shaft will cause no increase of pressure on the
spring-latch assembly, thereby protecting all
parts from excessive stress.

In Figure 6 is shown an end view of the jaws
of the clamping mechanism and their dimen-
sional relationships. 20

In Figure 5 is clearly shown in detail the de-
vice employed for mounting the supporting stage
59 of the latching mechanism on brackets 60
of the door machine. This device has been de-
veloped to furnish said stage with some end-wise
25 motion so that in those instances when the stage
has been elevated into operating position and
the fixed jaws of the clamping arrangement are
not in direct contact with the yoke of the spring-
latch, said jaws can be shifted into that position
30 by moving the stage end-wise. This movement
for allowing the jaws to center themselves is
provided by means of a crank-suspension device
comprising the crank-shaft 61 and the crank-
pin 77; the former is rotatably mounted in 35
bracket 60 and the latter is rotatably connected
with the stage to support it.

In the operation of my invention, subsequent
to the steps of stationing the door-machine in
front of the oven door, that is about to be re-
moved from its associated cooking chamber, and
of engaging bumper 50 in bumper-plate 51, door-
hook 52 is slowly raised from the position shown
in Figure 2 by starting motor 54. Stages 59 lo-
cated above and below said door-hook and con-
nected therewith respectively by rods 62, 63, start
40 to rotate around crank-pins 77 at the same time,
thus elevating the jaws of the clamping mecha-
nisms in the direction of the spring-latches
holding the door in the oven mouth. Connecting 45
rods 62, 63, are provided with such respective
lengths that when the door-hook is in substan-
tially the position shown in Figure 2, that is, when
said hook is in such position that it is about
to engage hook-plate 78, the jaws 67, 68, of the
50 clamping mechanisms will have engaged their
respective spring-latches and the horizontal sec-
tions of the fixed jaws will lie substantially ad-
jacent the lower parts of the yokes of the spring-
latches. When the door-hook and clamping 55
mechanisms are in these respective positions, the
door-hook drive is stopped and motor 64, which
is adapted to actuate the clamping mechanism,
is set in motion to rotate hollow shaft 73 in that
direction which will cause movable jaw 68 to 60
advance in ways 69 towards the spring-latch as-
sembly and into contact with the channel-cas-
ing member thereof. In the event that fixed
jaw 67 is not in contact with yoke 34 of said
65 spring-latch assembly when contact is established
between the movable jaw and channel-casing 35,
the pressure of the former against the latter will
cause crank-pin 77 to move about crank-shaft
61, which movement in turn will cause stage 59
70 to move away from the oven door a short dis- 75

tance and bring the fixed jaw into contact with the yoke of the spring-latch. Subsequent to the establishing of contact between the spring-latch and both jaws of its clamping mechanism, further movement of the movable jaw 68 in the direction of the door brings the yoke and channel-casing closer together so that the latter presses against the metal plates of the spring-latch and with sufficient pressure to move said plates out of contact with the latch-hooks and to relieve, at the same time, the surface 39 of bracket 38 of any pressure from yoke 34. Motor 64 is stopped when the spring-latches are sufficiently free to be removed from their positions between the oven door and the latch-hooks. The next step in the operation of removing the oven door is to re-start motor 64 thereby further elevating the door-hook and causing it to enter into lifting engagement with door-hook plate 78. This operation effects further rotation of the therewith connected stages 59 about crank-pins 71, to lift them and the thereon mounted clamping mechanisms, which now have the spring-latches flexed between their jaws. At such time as the door-hook has been elevated into sufficient engagement with the hook-plate to carry the weight of the oven door, the spring-latches will have been raised out of the latch-hooks and above the upper level thereof thus leaving the oven door supported on the door-hook and the latches un-latched. The door may be now withdrawn from the oven mouth by moving the ram outward from the face of the battery.

When it is desired to restore the oven door to its latched position in the oven, the above-recited operating steps are repeated in reverse sequence.

Limit switches may be employed, if preferred, to set into or arrest the motion of the various working parts so that they may be brought into action in proper sequence automatically, thereby saving time and providing convenience of operation. For example, a limit switch can be employed to cut-off the power from the door-hook drive and start the motor operating the clamping mechanism when the latter has been raised by the door-hook into a position where it can effectively clamp the spring-latches, and such an arrangement can also be utilized to limit the travel of the movable jaw in either direction and to start the door-hook drive mechanism after the spring-latches have been sufficiently flexed to allow their being lifted out of operating position. It is also expedient to provide means which prevent the starting of motor 64 save at such times as the jaws of the clamping mechanism are in position around the spring-latch in order to avoid the possibility of running the movable jaw off the threads of its actuating shaft.

In consequence of wear and for other reasons, it may be desirable to adjust the position of the spring-latches in respect of the door-casting and the latch-hooks. Such adjustive refinements may be simply done by placing "riders" that are adapted to rest between the outer surface of yoke 34 and the surface 39 of bracket 38. This expediency may be employed either to increase the distance between the door casting and the yoke or to increase the pressure of the spring-latches against the latch-hooks. If it should be desirable to vary the amount of clamping movement, this may be effected by placing clips on the channel-casing at points where it comes into contact with the movable jaw, or washers 75 of diverse thicknesses can be employed, or thrust-bracket

66 may be mounted in such manner that it is adjustable end-wise. By means of these expediences it is possible to regulate both the pressure exerted by the spring-latches on the door and on the latch-hooks and also to provide such position for the spring-latches in respect of the jaws of the clamping mechanism that they will always be operatively received by said jaws when they are elevated into operating position.

The herein disclosed actuating mechanism for the spring-latches of coke oven doors has been adapted for placing in operating position by the movement of the door-hook and consequently the same source of power may be used for moving both these members. Such embodiment of the invention has the advantage that the proper disposition of the one member in respect of its co-acting part on the door automatically provides the desired position for the other, thus reducing the number of adjustments from those that would be required if the two mechanisms acted independently of each other. However, in certain instances it may prove advantageous to provide independent action for the door-hook and the spring-latch clamping mechanism, which provision will depend largely on the construction of the door machine with which it is proposed to have the invention associated.

In both the hereinabove mentioned co-pending application and in the present description of a mechanism for actuating a spring-latch for a coke oven door, the spring-latch has been shown as a unit assembly having as one of its important features a device for carrying a pressure applied thereto to points adjacent the extremities of the spring-leaves where they are brought into contact with the latch-hooks. This device has been embodied as the channel-casing 35 and forms an integral part of the spring-latch. It is however obvious that more especially for those instances where the spring-latch is designed for employment in combination with a clamping mechanism of the herein disclosed type, the channel-casing need not be incorporated in the spring-latch assembly as a necessary element thereof for it is possible to combine said channel-casing and the movable jaws into one member without departing from the spirit of the invention or the operating results produced by the improvement. For example, I may if I prefer form the spring-latch as a simple assembly of spring-leaves held together in any appropriate manner that will not reduce their resilience substantially and combine the channel-casing and the movable jaws of the clamping mechanism into one member; or I may form the movable jaw 68 with lateral projections disposed to engage the spring-latch at points nearer the ends thereof than those where the pressure of the fixed jaws 67 is applied.

The invention as hereinabove set forth is embodied in particular form and manner but may be variously embodied within the scope of the claims hereinafter made.

I claim:

1. In combination with a coking retort oven having a movable door adapted for support in the mouth of the oven by a latching device comprising, a flexible and resilient member comprising plates coacting together as a spring and disposed both to span said door and to engage means that are independent of the door for arresting said member while under flexion, and means for transmitting clamping-pressure from an extraneous source to at least three points along said flexible and resilient member and of which

points two lie on the same side of said member and the third lies on an opposite side thereof substantially intermediately of the others, a clamping mechanism for actuating said flexible

5 and resilient member to latch and unlatch said door, said mechanism comprising: jaw-like parts that are adapted to engage between them both the flexible and resilient member and the means for transmitting clamping-pressure to said member at desired points therealong and in such manner that pressure can be applied to said member from opposite sides thereof simultaneously, and means for altering the distance between the jaw-like parts so as to modify the resilient pressure

15 obtaining in said flexible and resilient member.

2. A clamping mechanism for altering the flexure obtaining in latching means for a coke oven door so as to latch and unlatch said door, said latching means comprising: a spring-like

20 bar-element whose extremities can be flexed in respect of the intermediate parts thereof, disposed to span said door; hook means that are positioned at either side of said door and independently thereof, said hook means being adapted

25 to engage said spring-like bar-element and to arrest it while under flexion; and means for transmitting clamping-pressure to said spring-like bar-element in such manner that the extremities can be moved in respect of the intermediate parts thereof and of the hook means, said mechanism comprising: jaw-like parts that are adapted to form a clamping device for engaging the pressure transmitting means and the

30 spring-like bar-element from opposite sides of said bar-element; means for adjusting the distance between said jaw-like parts; and means for moving the spring-like bar-element into and out of engagement with the hook means.

3. A clamping mechanism for altering the flexure obtaining in latching means for a coke oven door so as to latch and unlatch said door, said latching means comprising: a spring-like bar-element adapted to be flexed intermediate its ends, that is disposed to span said door; hook

45 means that are positioned at either side of said door and independently thereof, said hook means being adapted to engage said spring-like bar-element and to arrest it while under flexion; and means for transmitting clamping-pressure to

50 said spring-like bar-element in such manner that the extremities can be moved in respect of the intermediate parts thereof and of the hook means, said mechanism comprising: at least a pair of jaw-like parts adapted to form a clamping

55 device and to receive the spring-like bar-element and the pressure transmitting means therebetween, one of said parts being adjustably disposed in respect of the other and provided with a threaded section; and a member having threads

60 adapted to engage the threaded section of the jaw-like part, said member being rotatable in respect of said part.

4. A clamping mechanism for altering the flexure obtaining in latching means for a coke oven door so as to latch and unlatch said door, said latching means comprising: a latch bar-ele-

65 ment that is disposed to span said door having a spring-like member therefor with extremities that can be flexed relative to its intermediate

70 parts; hook means that are positioned at either side of said door and independently thereof, said hook means being adapted to engage said latch bar-element and to arrest it while under tension

75 of the flexion of the spring member; and means for transmitting clamping-pressure to said

spring-like member in such manner that the extremities can be moved in respect of the intermediate parts thereof and of the hook means, said mechanism comprising: at least a pair of jaw-like parts adapted to form a clamping device 5 and to receive the spring-like member and the pressure transmitting means therebetween, one of said parts being adjustably disposed in respect of the other and provided with a threaded section; a member having threads that are 10 adapted to engage said threaded section of the jaw-like part; and power-driven means for rotating said threaded member.

5. A clamping mechanism for altering the flexure obtaining in latching means for a coke oven 15 door so as to latch and unlatch said door, said latching means comprising: a hook engaging bar-part with a spring-like member therefor, disposed to span said door; hook means that are positioned at either side of said door and independently thereof, said hook means being adapted to engage said bar-part and to arrest it while under tension of the flexion of the spring-like member; and means for transmitting clamping-pressure to said spring-like member in such

20 manner that its extremities can be moved in respect of the intermediate parts thereof and the bar-part relative to the hook means, said mechanism comprising: a stage rotatably mounted on a transportable support and provided with

25 end-wise movement in respect thereof; and on said stage and supported thereby, a clamping device formed by at least two jaw-like members that are adapted to receive therebetween both the bar-part and its spring-like member and the

30 means for transmitting pressure provided by the clamping device to preferred points therealong, one of said jaw-like parts being adjustably disposed in respect of the other and provided with

35 a threaded section, and a rotatable member having threads that are adapted to engage the threaded section of the adjustably disposed jaw-like part, and power-driven means for rotating

35 said threaded member.

6. A clamping mechanism for altering the flexure obtaining in latching means for a coke oven 40 door so as to latch and unlatch said door, said latching means comprising: a spring-like mem-

ber having extremities that can be moved in respect of intermediate parts thereof disposed to

45 span said door; hook means that are positioned at either side of said door and independently thereof, said hook means being adapted to engage said spring-like member and to arrest it while

50 under flexion; and means for transmitting clamping-pressure to said spring-like member in such manner that its extremities can be moved in respect of the intermediate parts thereof and of the hook means, said mechanism comprising:

55 a stage rotatably mounted on a support and provided with end-wise movement in respect thereof; and on said stage and supported thereby, a clamping device formed by at least two jaw-like

60 members that are adapted to receive therebetween both the spring-like member and the means for transmitting pressure provided by the

65 clamping device to preferred points therealong, one of said jaw-like parts being adjustably disposed in respect of the other and provided with

70 a threaded section, and a rotatable member having threads that are adapted to engage the threaded section of the adjustably disposed jaw-

75 like part, and power-driven means for rotating said threaded member; and means for translat-

ing said stage into and out of engagement with the spring-like member.

7. A clamping mechanism as claimed in claim 5 and in which the means for rotating the threaded member comprises: a motor; a speed-reducer; and means for counteracting thrust resulting from the pressure of the rotatable and threaded member against the movable jaw-like part.

8. A clamping mechanism as claimed in claim 10 5 and in which the stage is rotatably mounted on another mechanism having hook means for handling the oven door, said stage being connected with said hook means by a linkage so that they can be moved concurrently.

15 9. A clamping mechanism as claimed in claim 5 and in which the stage is rotatably mounted on another mechanism having hook means for handling the oven door and by means comprising a crank-shaft and crank-pin whereby said 20 stage is provided with end-wise motion when subjected to rotary motion.

25 10. A mechanism for actuating means that are disposed to latch a movable door in the mouth of a coking retort chamber, said means comprising, a multiple leaf spring constituting a flexible and resilient member that is adapted both to span said door and to exert pressure simultaneously against both the door and arresting means that are positioned adjacent either side and independently of said door for engaging said member, said mechanism comprising: jaw-like parts disposed in at least two elements between which the flexible and resilient member is receivable, the series of jaw-like parts being adapted to 35 clamp said member between them by means of a device disposed to move at least one of said series in respect of the other so that the distance therebetween can be varied and the resilient pressure obtaining in said flexible and resilient member thereby altered.

40 11. A mechanism for actuating means that are disposed to latch a movable door in the mouth of a coking retort chamber, said means comprising, a laminated spring constituting a flexible and resilient member that is adapted both to span said door and to exert pressure simultaneously against both the door and arresting means that are positioned adjacent either side and independently of said door for engaging said member, said mechanism being adapted to engage said 45 flexible and resilient member and comprising: a number of jaw-like parts arranged to exert pressure on said member at at least three points, therealong and of which points two lie on the same side of said member and the third lies substantially intermediately of the others on an opposite side thereof, the jaw-like parts at one side of the flexible and resilient member being adjustably disposed in respect of those at the opposite side so that the distance therebetween can be varied for the purpose of varying the fiction of said member.

45 12. In combination with a coking retort oven having a movable door adapted for support in the mouth of the oven by latching means comprising a hook engaging bar-part with a spring-like member therefor, disposed both to span said door and to engage means that are independent of the door for arresting said member while under flexion, a clamping mechanism for actuating said 50 spring-like member to latch and unlatch said door, said mechanism comprising: jaw-like parts on a movable stage one of which is fixed to the stage and another of which is provided with ways movable in grooves in fixed relation to the stage,

5 to exert clamping pressure against the spring-like member; a cylindrical bore in the movable jaw having threads; a threaded shaft rotatable for advancing and retracting the movable jaw; means for varying the distance between the jaw-like parts when they are in clamping position so that the clamping pressure exerted thereby can be regulated; and means for distributing the pressure exerted by said mechanism in such manner that it will be applied to the spring-like member at at least three points therealong and of which points two lie on the same side of said member while the third lies between the others and on the opposite side thereof.

10 13. A coke-oven door and door-operating apparatus, comprising in combination: the coke-oven door; spring means spanning said door and adapted to be flexed between its ends to secure it in place; and a power-actuated apparatus having cooperatively combined with each other a clamping mechanism for gripping, flexing, releasing and resetting said spring means.

15 14. A coke-oven door and door-operating apparatus, comprising in combination: the coke-oven door; spring means spanning said door and 20 adapted to be flexed between its ends to secure it in place; and a power-actuated apparatus adapted to travel from door to door along the oven-battery and having a clamping mechanism for gripping, flexing, releasing and resetting said 25 spring means.

20 15. A coke-oven door and door operating apparatus, comprising: a coke-oven door, a latch spanning said door and adapted to secure it in place against a holding means therefor, said latch 30 comprising a latch bar-element having spring means for exerting spring pressure on the latch bar-element intermediate its ends to tighten it between the holding means and door, and said latch bar-element and its spring means being bodily insertable and removable as a unit freely 35 displaceable relative to the door for insertion and removal between the door and the holding means; and a power-actuated apparatus adapted for removing, retaining for replacement, and replacing the latch bar-element as a unit relative 40 to the door, and having a clamping mechanism for gripping, flexing, releasing and resetting said 45 spring means.

45 16. In mechanism for actuating a resilient compressible member for spring tightening latch bar-means for coke-oven doors, a clamping mechanism comprising opposing clamp jaws on a stage movable into and out of positioning relation relative to the compressible member; one of the jaws being fixed relative to the stage and the other 50 being movable relative to the stage; ways- and groove-means for guiding the movement of the movable jaw; a bore in the movable jaw having at least a portion thereof threaded; and a 55 threaded rotatable shaft therefor, for advancing and retracting the movable jaw relative to the jaw that is fixed as to the movable stage.

55 17. Mechanism as claimed in claim 16, and which includes a thrust-bearing for the rotatable 60 shaft; a thrust-bearing engaging-element on the rotatable shaft located between the thrust-bearing and the threads of the rotatable shaft.

65 18. Mechanism as claimed in claim 16, and which includes a thrust-bearing for the rotatable 70 shaft; a thrust-bearing engaging-element on the rotatable shaft located between the thrust-bearing and the threads of the rotatable shaft, said engaging-element being spaced from the thrust 75

bearing to receive adjustable spacer elements therebetween.

19. Mechanism as claimed in claim 16, and in which a portion of the end of the rotatable shaft nearest the jaws is designed to be adapted to be out of threaded engagement with the threads of the bore of the movable jaw.

20. Mechanism as claimed in claim 16, and

which includes a crank-suspension for the stage, operable on rotation of the shaft when the movable jaw is in clamping engagement but the fixed jaw is not, for shifting the stage relative to the compressible member to bring the fixed jaw also ⁵ into clamping engagement.

GUSTAF EDWIN SALKVIST.
